UNITED STATES PATENT OFFICE.

DOUGAL J. MCKENZIE, OF CHICAGO, ILLINOIS.

FIRE-ARCH FOR FURNACES.

SPECIFICATION forming part of Letters Patent No. 768,966, dated August 9, 1904.

Application filed December 24, 1903. Serial No. 186,433. (No model.)

To all whom it may concern:

Be it known that I, DOUGAL J. MCKENZIE, a citizen of the United States, residing at Chicago, in the county of Cook and State of Illinois, have invented certain new and useful Improvements in Fire-Arches for Furnaces, of which the following is a specification.

The invention relates to that class of furnaces which are provided with fire-arches across the front portion and above the grate, and particularly to the construction and arrangement of parts by which such parts may be easily repaired and renewed, all of which will more fully hereinafter appear.

15 The principal object of the invention is to provide a simple, economical, and efficient fire-arch for furnaces.

Other and further objects of the invention will appear from an examination of the drawings and the following description and claims.

The invention consists principally in a fire-arch for furnaces in which there are combined a cross-beam arranged transversely across the furnace, a plurality of inwardly-extending brackets secured thereto and extending inwardly therefrom, and a plurality of longitudinally-disposed bars detachably secured one to each of such inwardly-extending brackets and fire-brick tiles detachably secured to each of such longitudinal beams.

30 The invention consists, further and finally, in the features, combinations of details of construction hereinafter described and claimed.

In the accompanying drawings, Figure 1 is a longitudinal sectional elevation of a fire-arch for furnaces as it appears when constructed in accordance with these improvements; Fig. 2, a cross-sectional elevation of the box-beam, showing a bracket and longitudinal beam as they appear in connection therewith and with all the other parts removed; Fig. 3, a cross-sectional elevation of a fire-arch, taken about line 3 of Fig. 2 looking in the direction of the arrow; Fig. 4, a side elevation of one of the longitudinal beams; Fig. 5, a plan view of the same; Fig. 6, a cross-sectional detail of one of the fire-bricks with its metal insert at the inner end of the arch, taken on line 6 of Fig. 3; Fig. 7, a cross-sectional elevation

taken on line 7 of Fig. 2, and Fig. 8 a cross-sectional detail taken on line 8 of Fig. 2.

In illustrating and describing these improvements I have only illustrated and will here describe that which I consider to be new, taken in connection with so much as is old as is necessary to properly disclose the invention to others, leaving out of consideration other and well-known mechanisms which if illustrated and described herein would only tend to confusion, prolixity, and ambiguity.

In constructing a fire-arch for furnaces in accordance with these improvements I take a box-beam *a* and arrange it transversely across the front portion of the furnace-chamber and above the grate-bars in any usual or ordinary manner, all of which is so well known in the art that it needs no further description or illustration herein. I next provide a plurality of supporting-brackets *b* and secure them by means of bolt-nut mechanism *c* to the inner upper side of the box-beam, as shown particularly in Figs. 2 and 3. These brackets, as above stated, are secured to the inner upper side of the box-beam and extend inwardly therefrom—that is, toward the rear of the furnace-chamber—and are provided with dovetail grooves *d* in the lower portions thereof.

A plurality of longitudinal beams *e* is provided, one for each of the inwardly-extending brackets, each of which has a dovetail portion *f*, adapted to engage with the dovetail grooves in the inwardly-extending brackets and be supported thereby. These longitudinal beams are of such length that they extend entirely under the box-beams and considerably to the rear or inwardly from the brackets, as shown particularly in Figs. 1 and 2. Their flanged portions are notched or cut away, as at *g*, and are of such a length as to permit of insertion or removal of the same from engagement with the brackets without drawing the longitudinal beams the entire length of the same. The dovetail portions of the forward end of the longitudinal beams are passed between lugs *h* on the lower forward surface of the box-beams, so as to position such longitudinal beams or, in other words, to prevent lateral displacement of the forward ends of the

same. The rear portions of the longitudinal beams are provided with web portions *i*, extending over and in engagement with the inner ends of the bracket mechanisms, as shown 5 in Fig. 2, to assist in holding the parts in position. These longitudinal beams are provided with T-shaped grooves *j* in the lower portion, the functions of which will more fully hereinafter appear.

- 10 To complete the fire-arch and provide means for protecting the metal parts thereof from the intense heat of the furnace, as well as to store up in a measure quantities of radiant energy, a plurality of fire-brick or tiles 15 *k* is provided for each longitudinal beam, and each of these tiles is grooved at its upper portion, so as to completely span the lower portions of the longitudinal beams. Each of these fire-bricks is provided with a T-headed 20 metal insert *l*, the lower conical portions *m* of which are inserted in recesses in the fire-brick or tiles and anchored therein by means of the surrounding metal *n*, which is poured therein while in a molten state. These T- 25 shaped inserts are used for the purpose of detachably securing and holding the fire-brick or tile in position. The ordinary fire-brick *p* and "grout" *q* are used to complete the surrounding of the metal parts, as shown in Figs. 1 and 3, 30 and protect the same from intense heat, all of which will be understood and appreciated by those skilled in the art.

I claim—

1. In a fire-arch of the class described, the 35 combination of a cross-beam arranged transversely across the furnace, a plurality of inwardly-extending brackets secured thereto and extending inwardly therefrom, a plurality of longitudinally-disposed bars detachably 40 secured one to each of such inwardly-extending brackets, and fire-brick tiles detachably secured to each of such longitudinal bars, substantially as described.

2. In a fire-arch of the class described; the 45 combination of beam mechanism arranged transversely across the furnace, a plurality of brackets attached thereto and extending inwardly therefrom, a plurality of beams longitudinally disposed and removably attached 50 to the inwardly-extending brackets and provided with grooves in the lower portion thereof, and a plurality of fire-brick or tile provided with portions engaging the groove mechanism of the longitudinal beams to permit the easy insertion or removal of said tile mechanism, substantially as described.

3. In a fire-arch of the class described, the 60 combination of a metal box-beam extending transversely across the furnace, a plurality of brackets attached to the rear portion thereof and extending inwardly therefrom, a plurality of longitudinal beams—one for each inwardly-extending bracket—detachably secured to said brackets, and a plurality of fire-

brick or tiles provided with metal inserts 65 detachably engaged with the longitudinal beams, substantially as described.

4. In a fire-arch of the class described, the combination of transversely-arranged beam mechanism, a plurality of brackets attached thereto and extending inwardly therefrom, a plurality of longitudinally-arranged beams provided with grooves in their lower portions 70 detachably secured to the inwardly-extending brackets, and a plurality of fire-brick or tiles 75 provided with T-shaped insert-pieces anchored therein and detachably engaging with the grooves in the longitudinal beams, substantially as described.

5. In a fire-arch of the class described, the 80 combination of a metal beam transversely disposed, a plurality of brackets secured thereto and extending inwardly therefrom and provided with a dovetail groove in the lower portions thereof, a plurality of longitudinal 85 beams provided with dovetails in the upper part detachably engaging the grooves in the inwardly-extending brackets and further provided with groove mechanism in the lower portion thereof, and a plurality of fire-brick 90 or tile mechanism provided with metal inserts detachably engaging the groove of the longitudinal beams, substantially as described.

6. In a fire-arch of the class described, the combination of a box-beam transversely arranged, a plurality of brackets secured to the inner side thereof and extending inwardly therefrom and provided with dovetail grooves in the lower portions thereof, a plurality of longitudinal beams provided with groove 100 mechanism in the lower portion thereof and dovetail mechanism detachably engaging the groove mechanism of the inwardly-extending brackets, and a plurality of fire-brick or tiles provided with metal portions detachably engaging the grooves of the longitudinal beams, 105 substantially as described.

7. In a fire-arch of the class described, the combination of a metal box-beam transversely disposed, a plurality of brackets attached to the inner upper side thereof and extending inwardly therefrom and provided with a dovetail groove in the lower portion, a plurality of longitudinal beams provided with grooves in the lower portions and with dovetails in 115 the upper portions thereof detachably engaging the grooves of the inwardly-extending brackets, a plurality of fire-brick or tile mechanism to surround and protect the lower portion of the metal parts, and T-shaped metal inserts anchored in each fire-brick or tile to detachably secure the same in operative position on the longitudinal beam mechanisms, 120 substantially as described.

8. In a fire-arch of the class described, the 125 combination of a metal box-beam transversely disposed, a plurality of brackets attached to the inner upper side thereof and extending

inwardly therefrom and provided with a dovetail groove in the lower portion, a plurality of longitudinal beams provided with grooves in the lower portions and with dovetails in the upper portions detachably engaging the grooves of the inwardly-extending brackets, lug mechanism on the lower forward portion of the metal box-beam to prevent lateral displacement of the forward ends of the longitudinal beams, substantially as described.

9. In a fire-arch of the class described, the combination of a metal box-beam transversely disposed, a plurality of brackets attached to the inner upper side thereof and extending inwardly therefrom and provided with dovetail grooves in the lower portions thereof, a plurality of longitudinal beams provided with a T-shaped groove in the lower portion and a dovetail groove in the upper portion in detachable engagement with the dovetail groove of the inwardly-extending brackets extending entirely under and to the forward end of the box-beam and projecting inwardly from the inwardly-extending brackets, an upper web portion on the longitudinal beams extending over a portion of the brackets to assist in positioning said beams, lug mechanism on the lower surface of the box-beam in engagement with the longitudinal beams to prevent lateral displacement of the same, and a plurality of fire-brick mechanism provided with T-shaped metal inserts in detachable engagement with the grooves in said longitudinal beams, substantially as described.

35 10. In a fire-arch of the class described, the

combination of metallic cross-beam mechanism arranged transversely across the furnace, a plurality of longitudinally-disposed metal bars detachably supported by such cross-beam mechanism, and fire-brick tiles provided with metallic inserts detachably secured to such longitudinally-disposed bars, substantially as described.

11. In a fire-arch of the class described, the combination of cross-beam mechanism arranged transversely across the furnace, a plurality of longitudinally-disposed bars supported by such cross-beam mechanism, each of which is provided with a longitudinally and centrally disposed groove, and fire-brick tiles provided with centrally-disposed metallic inserts detachably engaging the grooves of the longitudinally-disposed bars, substantially as described.

12. In a fire-arch of the class described, the combination of metal cross-beam mechanism arranged transversely across the furnace, a plurality of longitudinally-disposed metal bars detachably supported by such cross-beam mechanism, fire-brick tiles provided with metallic inserts, groove mechanism in one of such parts, and intermeshing head mechanism in the other part for detachably supporting the metallic inserts with the fire-brick tiles in position, substantially as described.

DOUGAL J. MCKENZIE.
